UNITED STATES PATENT OFFICE.

RUTHERFORD B. HARRIS, OF OCEAN PARK, CALIFORNIA.

LOCK-FOLD EXPANDING INDEXING TICKET FILE.

Application filed July 26, 1921. Serial No. 487,817.

To all whom it may concern:

Be it known that I, RUTHERFORD B. HARRIS, a citizen of the United States, residing at Ocean Park, in the county of Los Angeles and State of California, have invented a new and useful Lock-Fold Expanding Indexing Ticket File, of which the following is a specification.

This invention is applicable for filing various forms of paper slips, tabs or cards.

It is more particularly intended for filing deposit slips in banks.

At present, banking institutions file their deposit slips according to dates; all of the deposit slips for each banking day being placed together and stored away for future reference. It is desirable that they be readily accessible and that the slips for each day throughout any desired term of years may be easily found and inspected. The number of deposit slips for each day for many banks is so limited that the same, when put together ordinarily form a bundle, an inch or less in thickness for all depositors, from A to Z, and when a greater number of slips is required for one day's deposits, the slips may be assembled in units as desired, as for instance, bundles from A to G, H to K, etc.

Such slips are usually in the neighborhood of $3\frac{1}{4}$ by $5\frac{1}{2}$ inches outside dimensions and are provided at the top with an inscription giving the name of the bank, followed by blanks into which are written the name of the depositor and the date of the deposit. Below this are arranged in columns the items indicating the character and amount of the deposit.

This invention is particularly intended for use in filing bank deposit slips, sales slips, debit and credit tickets, order slips, or any other loose leaf slips or memoranda where permanency and facility for ready reference is desired.

In this invention I provide two flaps of thick tag board or other suitable flexible material; and constituting two folds, viz, a back section, and a front section of less length than the back section; the same being united by a bent section.

The front section is provided with lateral extensions and the back section is provided near its margin, with two longitudinal slits adapted to receive the lateral extensions for the purpose of holding the front section in folded position.

The exact dimensions of the sections, the

slits and the lateral extensions may be changed to conform to different shapes of cards, slips or papers to be filed, and the lateral extensions are preferably made by fastening a straight strip of tag board to the free end of the front section, and bending said strip around the edges of the back section, and then inserting the ends through the slits.

The standard size of the folded file for bank deposit slips may be $3\frac{3}{8}$ inches by 6 inches, closed, with a capacity of from 1 to 200 slips for each file, and can be made in any size or shape to conform to any of said

slips.

An object of the invention is ease and facility of manufacture and use; and an advantage of the invention is the perfect ease and facility with which the individual slips in each packet, bundle or unit may be found.

Advantages are, ease to manipulate; the packets stack flat in file cases; the front and back faces of the packets are smooth; no snaps, buttons or fasteners are present to catch and tear when the package is inserted or removed from the case; no rubber bands to break, nor string or tape to untie, and yet examination of any slip without breaking or destroying the package is permitted and a tab is allowed to project and to permit indexing by date, numerically, alphabetically, or both.

Other objects, advantages and features of invention may appear from the accompanying drawings, the subjoined detail description and the appended claims.

The accompanying drawings illustrate the invention.

Figure 1 is a perspective front view of a ticket file constructed in accordance with this invention, folded and filled with deposit slips, and ready for filing.

Fig. 2 is a plan of a file made of two separate blanks fastened together and ready for folding and filling.

Fig. 3 is a perspective front view of the invention as it may appear at one stage in the operation of binding a bundle of deposit slips.

Fig. 4 is a perspective rear view of the file just before it is entirely closed.

Fig. 5 is a back view of the closed file ready for storing.

Fig. 6 is a front face view of the filled file.

Fig. 7 is a cross section on line x^7 , Fig. 6.

Fig. 8 is a section on line x^8 , Fig. 6, the

free ends of the slips being shown bent forward.

Fig. 9 is a perspective view of a number of files embodying my invention and stored 5 for use in a file case.

The main strip 1 comprises a back section 2, a front cover 3 and a fold 4 between the back section and the front cover. Said fold 4 may be formed by one or more creases 5 10 extending across the strip. The front cover 3 is of less length than the back section so that when it is folded onto the back section a slight space is left above the upper edge of the front section and below the upper 15 edge of the back section in which will be exposed the upper portion of the foremost one of the slips that are filed; and the top of the back section is provided with a space 6 in which the date 7 may be stamped by the 20 file clerk.

The space 8 between the date space 6 and the fold 4 is sufficiently long to accommodate the papers or slips 9 to be filed. The binding elongate straps 10 are formed of a comparatively narrow strip preferably of the same tag board or such other material as the main folder, and the back 2 is provided with longitudinal slits 11 which are preferably near and parallel to the longitudinal edges 25 of the back section, and are as much greater in length than the width of the binding flaps, as is necessary to allow ample room for receiving the binding flaps at all positions to which the same may be brought by reason 30 of the greater or less take-up of the fold caused by the variations in thickness of the 35 packet of slips.

Said elongate straps are of considerable length as shown, so as to accommodate ticket 40 or slip stacks or packages of greater or less thickness.

In practical use, the slips to be filed are sorted in the order desired, all double length and other odd length slips are folded to the 45 standard length from the bottom. The slips are then evenly stacked and placed on the open folder as indicated in Fig. 1, thus leaving the top of the slips all even and about one-half inch from the top of the 50 folder.

The bottom part of the folder is then folded over the first of the tickets or slips and the stack is then pressed down tightly and the folder sharply creased with the fingers along the back and front corners of the stack. The position of the front may vary according to the thickness of the packet. The packet is then turned onto its face, as shown in Fig. 4, and the binding flaps are 55 folded over and across the back, and are pressed down firmly and then creased sharply with the fingers across the edges of the back. The ends of the binding straps 60 are then inserted into the slits 11 in the back cover and pushed through as far as they will 65

go. The resiliency of the material and the pressure from within the package, holds the binding straps in place and the completed package after being properly indexed as at 70 7 upon the projecting tab at the top, is then ready for the permanent file.

When it is desired to inspect any particular ticket or slip the dates of the files are 75 easily noted by looking into the top of the filing case 12, and the projecting tab formed by the top of the back section can be taken hold of by the thumb and finger and the file removed and the packet withdrawn and returned at pleasure. The stacks of tickets 80 in the file packets hold the tabs apart so they can be taken hold of individually by the thumb and finger.

When a package is removed from a filing 85 case 12 for examination, the slips can be turned outward from rear cover 2 or downward over the short front cover 3 as indicated in Fig. 8 so that any individual slip 90 can be found easily and removed from the package without removing all of the slips from the folder.

The cross-strip or strap 13 which terminates in the elongate straps 10 may be attached to the front fold 3 by paste, glue or staples or any other suitable means and is 95 practically of one piece with the same. Staples 14 are shown as the fastening means suggested in the drawings.

I claim.

1. A ticket file comprising a strip of flexible material formed with a back section and a front section and with an intermediate bendable section and adapted to enfold a stack of sheets to be filed; said back section being provided with slits and said front section being provided with elongate straps adapted to fold around the edges of the stack and around the edges of the back section and there to be inserted into said slits and adjustable in the slits for the purpose of accommodating sheet stacks of different thicknesses and to form fasteners for holding the folders on the stack.

2. A ticket file comprising a strip of material having a front section and a slit back section, said sections being integrally connected by a flexible intermediate section; elongate straps attached to the front section and adapted to fold around and to be inserted into the slits in the back section so as to accommodate the ticket or slip packages of greater or less thickness.

3. A ticket file comprising a strip of material having front and back sections that are integrally connected by a flexible intermediate section that forms a bottom for the ticket file; said back section having elongated slits and said intermediate section being adapted to be bent to a wide or narrow width to fit different thicknesses of

slip or ticket passages, and straps fixed to the front section and adapted to be folded over the longitudinal edges of the back section and inserted into slits therein for the 5 purpose specified.

4. A ticket file comprising a strip of material having a short front section and a long slitted back section that are integrally connected by a flexible intermediate section that 10 forms a bottom for a ticket file; said intermediate section being adapted to be bent to wide or narrow widths to fit slip or ticket packages of different thicknesses, and straps attached to the top of the front section and 15 adapted to be folded over the longitudinal edges of the front and back section and inserted in the elongated slits in the back section for the purpose specified.

5. A ticket file comprising a strip of material having a short front and a long slitted back section that are integrally connected by a flexible intermediate section; and flaps connected to the front short section that are insertable in slits in the back section to 25 hold the front and back sections in clasping engagement with a package of slips or tickets between them so that any slip or ticket can be examined, or removed from the package, without releasing the clasping engagement of front and back sections 30 with the package of slips or tickets.

6. A ticket file comprising a strip of material having a short front and a long slitted back section that are integrally connected by a flexible intermediate section, flaps connected to the front short section that are insertable in slits in the back section to 35 hold the front and back sections in clasping engagement with a package of slips or tickets between them so that any slip or 40

ticket can be examined or removed from the package without releasing the clasping engagement of front and back sections with the package of slips or tickets, there being tabs on the back section whereby ticket files 45 can be arranged in a filing case so that the date of each ticket file is visible without removing from the filing case and the file can be easily removed from the case without disturbing the file of any other date. 50

7. A ticket file comprising a strip of material having a front section and a slit back section, said sections being integrally connected by a flexible intermediate section; flaps formed of a strip stapled to the front 55 section and adapted to fold around and to be inserted into slits in the back section for the purpose specified.

8. A ticket file comprising a strip of material having a front section, a back section 60 and a flexible intermediate section and adapted to be bent into position for embracing a package of slips or tickets between the front and back sections; said back section having longitudinal slits of considerable 65 length; and straps connected to the front section and of considerable length and adapted to be bent around such package of slips or tickets and inserted into the slits in the back section; said straps 70 being narrower than the slits in the back section so as to accommodate different thicknesses of slip or ticket packages.

In testimony whereof, I have hereunto set my hand at Los Angeles, California, 75 this 18th day of July, 1921.

RUTHERFORD B. HARRIS.
